UNITED STATES PATENT OFFICE

2,266,072

TYPOGRAPHICAL CASTING MACHINE

James C. Plastaras, Laurelton, N. Y., assignor to
Mergenthaler Linotype Company, a corporation
of New York

Application April 25, 1939, Serial No. 269,833

21 Claims. (Cl. 199—47)

This invention relates to typographical casting machines, such as Linotype machines of the general organization represented in U. S. Letters Patent to O. Mergenthaler, No. 436,532, wherein a melting pot or so-called "metal pot" is arranged to deliver molten metal into a slotted mold and up against a composed line of matrices to produce a type bar or slug bearing on its edge type characters corresponding to the intaglio characters of the matrices.

In these machines, the molten metal is introduced into the mold by means of a spring-actuated pump piston or plunger arranged within the pot and controlled in its action by a rotary cam which, as well known, makes one complete rotation for each cycle of operation of the machine. The cam is so shaped as normally to maintain the pump plunger in a raised position out of action, and at one point in its circumference is formed with a depression which, at the proper time, permits the plunger to descend more or less gradually and uniformly under the influence of its actuating spring to fill the mold with molten metal for the casting operation. The metal pot is formed with a throat having a passage leading upwardly from a well at the bottom of the pot to a mold engaging mouthpiece standing at a height above the level of metal in the pot and, hence, above the level of the metal in the throat prior to casting.

With this arrangement, upon the descent of the plunger to force metal from the pot into the mold, a large volume of metal has to be displaced to fill the throat before the actual introduction of the metal into the mold; and a corresponding volume of air is displaced and forced into the mold from the throat and exhausted from the mold as the latter fills with metal. The exhaust of air from the mold has always been troublesome because of the fact that the mold is artificially cooled and some of the air may become trapped by the formation of a film of solidified metal against the walls of the mold before the mold is completely filled. The air which is trapped in the mold results in the production of a slug having a porous or spongy texture, rendering it unfit for use because of the likelihood of its breaking down or because of its having a defective casting face in the event that air has become trapped in the regions of the intaglio characters punched in the matrices. Moreover, the pressure exerted on the metal by the plunger is not uniform throughout the metal injecting stroke of the plunger, due to the relaxation of the plunger-actuating spring, so that the metal enters the mold under a gradually diminishing

pressure, and hence, at a gradually diminishing velocity.

Furthermore, these machines are equipped with molds of different sizes adapted to be selectively brought into use, and the same spring-actuated plunger is relied upon to inject the metal into the mold regardless of its size. Thus, the texture or density of slugs of different sizes is necessarily not uniform; and this condition is further aggravated by reason of the accumulation of metal oxide on the walls of the upper portion of the throat, the oxide deposit choking the throat passage and decreasing the volume and speed of the metal which can be forced therethrough under the pressure of a spring of given tension. These and many other difficulties are well known to the art, and it would serve no useful purpose to discuss the matter further.

The primary object of the present invention is to obviate the foregoing difficulties and, to this end, the invention provides an improved form of metal pot and metal injecting mechanism, as well as an improved form of pot mouthpiece wiper. In its broader aspects, the invention provides a metal pot and metal injecting mechanism adapted to subject metal in the pot to pressure and then suddenly release the metal for introduction into the mold while exerting a substantially uniform pressure thereon. More specifically, the metal pot is mounted to move horizontally into and out of casting relation to the mold and is formed with a well located below the main body of metal therein. A short, nearly horizontal throat is provided, which communicates with the well through a relatively small circular port and flares laterally therefrom to the pot mouthpiece, being divided by vertical partitions into a plurality of separate passages of substantially uniform cross-sectional area throughout their lengths. The port between the well and the throat is normally closed by a positively operated ball valve, which is opened and closed in timed relation to the operation of the plunger. The plunger works in a cylinder communicating with the well and immersed in the main body of molten metal in the pot, and is actuated by a fluid (preferably compressed air) operated piston controlled by a valve to effect both the metal injecting stroke of the plunger and its retraction after the mold is filled with metal. Normally, the plunger-actuating piston is maintained under a full head of pressure and held against movement by a trip dog. When the dog is tripped to release the piston, the initial movement of the plunger closes

the metal inlet to the well and subjects the metal confined in the well to pressure. Thereafter, the valve is suddenly opened and the plunger completes its stroke to inject the metal into the mold under uniform pressure and at a high velocity, forming a dense slug body having a casting face of complete, sharply defined characters by filling the mold and the intaglio characters in the matrices completely before the metal has an opportunity to chill and solidify.

The pot mouthpiece wiper is adapted to clean the mold engaging surface of the mouthpiece just before the latter engages the mold for the casting operation, and comprises a wiping element which is mounted to yield relatively to its support to avoid interference with the mold carrier when in casting position.

In the accompanying drawings, the invention has been shown merely by way of example and in preferred form, but obviously many variations and modifications may be made therein which will still be comprised within its spirit. It is to be understood, therefore, that the invention is not limited to any specific form or embodiment except insofar as such limitations are specified in the appended claims.

Referring to the drawings:

Fig. 1 is a side elevation of the casting mechanism of the machine, partly in section and partly broken away to show the interior construction, the parts being shown in the position they occupy when out of casting relation;

Fig. 2 is a view similar to Fig. 1, showing the parts in casting relation;

Fig. 3 is an enlarged vertical section taken through the melting pot and associated mechanism, some of the parts being broken away;

Fig. 4 is a perspective view of the plunger lever attaching block;

Fig. 5 is a front sectional elevation, partly broken away, of the plunger releasing mechanism;

Fig. 6 is a front elevation, partly in section and partly broken away, of the metal pot and associated parts;

Fig. 13 is a top plan view of the yokes actuated by cams on the main cam shaft; and

Fig. 14 is a vertical section taken through the air control valve box for the plunger operating piston.

Figs. 1 and 2 are contrasting views of the improved casting mechanism, showing the relationship of the parts when out of and in casting position, respectively. The line of matrices M is presented to the face of the slotted mold A by the first elevator B, which is located in casting position by the banking of the adjusting screw b in the elevator head B¹ against the top surface c

5 of the vise frame C. The mold A is supported in a carrier A¹ and, as usual, comprises a lower body portion a and an upper cap portion a¹ spaced from the body by end liners (not shown) to form the mold cavity a².

In the present instance, the metal pot D is mounted on a carriage E supported in the machine frame F and adapted for horizontal fore and aft movement into and out of casting relation to the mold A. At its four corners, the carriage E is equipped with rollers e which ride in trackways f formed by channel members F¹ of the frame F (see Fig. 6). The pump actuating mechanism G is supported above the metal pot D in fixed relation thereto by posts E¹ rising from the carriage E to which they are rigidly secured. The movement of the pot D and the control of the pump mechanism G is effected by a series of cams on a rotatable cam shaft H arranged at the side of the pot D and operating through flexible connections which permit the movement of the pot D and pump mechanism G as a unit relatively to the cam shaft H. The cam shaft H is rotated from a suitable source of power through a gear H¹ fixed thereto, making one complete rotation during each cycle of operation.

The metal pot D (Figs. 3, 6 and 7) comprises an outer jacket d which surrounds and is insulated by suitable material d¹ from the crucible D¹ containing the body of molten metal d². The bottom of the crucible D¹ is formed to provide a well D² located below the body of metal d² and separated therefrom by a wall d³. A metal delivery throat D³ is arranged in the front end of the well D² and is secured therein by screws d⁴ which clamp its flanged front end d⁵ to the flanged face d⁶ of the well, the throat D³ being spaced from the walls of the well D² so as to be surrounded at all times by the molten metal in the well. A passage d⁷ leads through the throat D³ from the well D² to a mouthpiece D⁴ secured to the front face of the throat, the passage d⁷ being relatively short and but slightly inclined upwardly toward the front where it 30 communicates with a series of openings d⁸ formed in the mouthpiece D⁴. As seen in Fig. 7, the rear end of the throat D³ is formed with a circular port d⁹ from which the passage d⁷ flares laterally toward the front of the throat, the passage d⁷ being divided by a series of vertical partitions d¹⁰ which are wedgelike in cross-section and define a plurality of channels d¹¹ of substantially uniform cross-sectional area throughout their lengths leading to the mouthpiece D⁴. A cylinder D⁵ rises from the wall d³ which forms the bottom wall of the crucible D¹ and the top wall of the well D², and at a predetermined level said cylinder is formed with a pair of diametrically opposite ports d¹² provided for the intake of metal d² from the crucible into the well. A plunger D⁶ is arranged for reciprocation in the cylinder D⁵, and it is connected by a rod d¹³ to the plunger actuating mechanism G, the rod being pivotally connected at one end to the plunger D⁶ by a wrist pin d¹⁴ and the opposite end being formed with a slot d¹⁵ by which the rod is detachably connected to the plunger actuating mechanism.

70 As seen in Figs. 7 and 11, a needle-valve D⁸ is screw threaded into two brackets d¹⁶ and d¹⁷, formed on the inner wall of the crucible D¹ and located one above the other, for adjustment vertically to locate its tapered end d¹⁸ relatively to an opening d¹⁹ in the wall d³. The valve D⁸ is

locked in its set position by the tightening of a screw D⁹ which bends the ends of the brackets d¹⁶ and d¹⁷ toward each other, the screw D⁹ being formed with a head d²⁰ which engages the top surface of the bracket d¹⁶ and a shank d²¹ extending through an opening in the bracket d¹⁶ and being screw threaded into an opening in the bracket d¹⁷. The opening d¹⁹ constitutes a bypass for the escape of metal from the well D² to the crucible D¹ to allow the plunger D⁶ to partake of a full stroke during each casting operation, regardless of the volume of metal injected into the mold.

A burner D⁷ for heating the metal is arranged beneath the crucible D¹ at a level below the bottom of the well D², in order to heat not only the main body of metal d² but also to keep the metal in a heated condition after it enters the well.

The reciprocation of the metal pot D is effected by a cam H² fixed to the shaft H and formed in its peripheral surface with a trackway h¹ (Fig. 1) adapted to receive a roller n journalled in the end of a short arm n¹ of a bell-crank lever N pivoted to the machine frame F on a shaft n² (Fig. 6). A long arm n³ of the lever N is connected to a rod n⁴ pivoted to one arm n⁵ of a bell-crank lever N¹, the other arm n²⁰ of which is connected to one end of a toggle link n¹⁰ having its opposite end connected to a lug e⁶ at the rear of the carriage E. The lever N¹ is pivoted as at n⁶ to the bifurcated head n⁷ of a bolt n⁸ extending through an opening in a fixed block n⁹ and being held by a nut n¹² threaded on the end of the bolt n⁸. The arm n³ of the bell-crank lever N is fastened to the rod n⁴ to slide relatively thereto and operate through a relief spring n¹³, the end of the arm n³ and the spring n¹³ being held between adjusting and lock-nuts n¹⁴ threaded on the rod n⁴. An adjusting yoke n¹⁵ is interposed between the head n⁷ of the bolt n⁸ and the front face n¹⁶ of the block n⁹, being formed with arms n¹⁷ adapted to straddle the block n⁹ vertically and carrying adjusting screws n¹⁸ which bear against parallel inclined surfaces n¹⁹ on the block n⁹. The yoke n¹⁵ is formed with a slot (not shown) which permits it to move vertically relatively to the bolt n⁸ when the nut n¹² is loosened. When the adjusting screws n¹⁸ are turned in one direction or the other, the yoke n¹⁵ moves up or down as the case may be, and since the face n¹⁶ of the block n⁹ and the surface of the yoke n¹⁵ engaging therewith are correspondingly inclined as shown, the resulting wedging action either moves the bolt n⁸ to the right or left, thus changing the location of the pivot n⁶ to adjust the pot D for a proper lock-up with the mold A in casting relation thereto.

As already stated, the pump plunger D⁶ is adapted to be reciprocated by pneumatically operated means, and for this purpose the pump actuating mechanism G comprises an air cylinder G¹ supported above the pot D on a cross-head E² (Figs. 5 and 9) connected to the upper ends of the posts E¹ rising from opposite sides of the pot carriage E. A double acting piston G² (Fig. 1) is arranged within the air cylinder G¹ and is adapted to be controlled by a valve V which admits air into the bottom or top of the cylinder G¹ to move the piston G² up or down. The opposite ends of the cylinder G¹ are closed by removable caps g¹ and g² which are clamped in place against the ends of the cylinder G¹ by bolts g³ passing through openings in bosses g⁴ formed on the upper cap g¹ and extending downwardly exteriorly of the cylinder G¹ with their ends threaded into openings formed in bosses g⁵ on the lower cap g².

The upper cap g¹ is formed on its inner surface with a recess g⁶ into which a sleeve g⁷ is fitted and which sleeve receives the upper portion g⁸ of the piston G². A compression spring g⁹ is arranged 5 to surround the sleeve g⁷ and bears against a shoulder g¹⁰ formed on the piston G². Below the shoulder g¹⁰, the piston G² is enlarged to provide a lower portion g¹¹ in sliding engagement with the inner surface g¹² of the cylinder wall. As 10 best shown in Figs. 1 and 5, an air pipe v leads from the valve V to the upper cap g¹, opening into the cylinder G¹ within the sleeve g⁷ and above the end of the upper portion g⁸ of the piston G²; and an air pipe v¹ leads from the valve V to a port g¹³ 15 formed in the side of the cylinder G¹ and which leads into the interior thereof below the lower end of the piston G².

The valve V (Figs. 1, 2, 5 and 14) is secured by a bracket e⁵ to the cross-head E² and comprises 20 two sections v² and v³ secured together by screws v⁴. The section v² is formed with a recess v⁵ in its inner face to accommodate a slide v⁶ pressed against the inner face of the section v³ by a leaf spring v⁷ secured by a screw v⁸ to the wall of the section v². Near its lower end, the slide v⁶ is formed with a drill hole v⁹ to accommodate a pin v¹⁰ formed on a plunger v¹¹ arranged to reciprocate in an opening v¹² at the bottom of the section v³ to raise and lower the slide v⁶, the plunger 25 v¹¹ normally being held in the lower position shown in Fig. 14 by a compression spring v¹³. A removable cover plate v¹⁴ secured to the outer face of the section v³ permits access to a compartment v¹⁵ in which the plunger v¹¹ and spring 30 v¹³ are arranged, the arrangement simplifying manufacture and the assembling of the parts.

As shown in Fig. 1, an air intake pipe J and an air exhaust pipe K are connected to the section v² of the valve V and communicate respectively 35 (Fig. 14) with ports v¹⁶ and v¹⁷, the former opening into the recess v⁵ of the section v² and the latter opening into a recess v¹⁸ in the slide v⁶. The pipes v and v¹ leading from the valve to the top and bottom, respectively, of the cylinder G¹ 40 communicate with ports v¹⁹ and v²⁰ in the section v³ of the valve. In the position of the parts of the valve as shown in Fig. 14, communication is established between the intake port v¹⁶ and the port v¹⁹ as indicated by the arrow, to supply air 45 to the top of the cylinder G¹, communication being established at the same time between the port v²⁰ and the exhaust port v¹⁷ through the recess v¹⁸ in the slide v⁶ to exhaust air from the bottom of the cylinder G¹. When the plunger v¹¹ is 50 raised, moving the slide v⁶ with it, communication is established through the recess v¹⁸ between the exhaust port v¹⁷ and the port v¹⁹ for the exhaust of air from the top of the cylinder G¹. At the same time, communication is cut off between the exhaust port v¹⁷ and the port v²² through an opening v²¹ formed in the slide v⁶ for the admission of air to the bottom of the cylinder G¹. It 55 may be well to state at this time that normally the valve parts occupy the position shown in Fig. 14 with a full head of air pressure maintained above the piston G², the slide v⁶ being moved upwardly but momentarily for the raising of the piston G² to retract the pump plunger D⁶ after casting.

The piston G² is held in its upper position 60 against the head of air pressure and the tension of the spring g⁹ by a dog O (Fig. 5), which engages beneath a block P secured by a screw pin p to the lower end of a piston rod g depending from 65 the piston G² within the cylinder G¹. The lower 70

75 piston G² within the cylinder G¹.

end of the block P is formed with an opening p^1 (see also Fig. 4) to receive a flat headed pin p^2 to which the upper end of the plunger rod d^{13} is adapted to be secured (Fig. 3), the slot d^{15} in the upper end of the rod d^{13} fitting over the pin p^2 and being held thereon by a pawl p^3 pivoted to the block P on a pin p^4 and pressed against the top edge of the plunger rod d^{13} by a compression spring p^5 . The dog O is supported on a roller O^1 and carries a roller o which engages the bottom edge of the head of the pin p^2 in the block P. The opposite end of the dog O is pivoted at o^1 to the end of one arm o^2 of a bell-crank lever O^2 pivoted at o^3 to the cross-head E^2 and normally held in the full line position shown in Fig. 5 by a spring o^4 arranged between the cross-head E^2 and an upstanding lug o^5 on the lever O^2 . The other arm o^6 of the lever O^2 extends toward the side of the machine in position to be engaged by actuating means for rocking the lever O^2 against the pressure of the spring o^4 to the dotted line position shown in Fig. 5 to retract the dog O and remove the roller o to its dotted line position clear of the block P and permit the descent of the plunger D^6 for the casting operation. The active position of the dog O, that is, the extent to which it projects beneath the block P, is determined by an adjusting screw o^7 abutting against the cross-head E^2 , the screw o^7 being threaded through an opening in the arm o^2 of the lever O^2 and locked in set position by a nut o^8 .

The descent of the plunger D^6 is adapted to control the opening of a ball valve X (Fig. 3) which closes the inner end of the throat passage d^7 in the well D^2 of the metal pot D, and to this end a valve-opening hammer T is arranged to be released by a trigger T^1 rockably mounted as at t with one arm t^1 in the path of an inclined surface p^6 on the block P, which surface p^6 engages the trigger arm during the descent of the block and rocks the trigger T^1 counterclockwise from its full line position, as determined by an adjusting screw t^2 held by a locknut t^3 , to the dotted line position, moving the other arm t^4 of the trigger T^1 out of engagement with the hammer T and releasing the latter to open the valve X. The trigger arm t^4 is relatively thick, being formed with an offset portion t^{28} (Fig. 8) with which the hammer arm t^{12} engages, so that when the hammer is released the arm t^{12} swings clear of the trigger arm t^4 at one side thereof.

The hammer T (Figs. 3 and 9) is forked to provide arms t^5 and t^6 and is fixed by a pin t^7 to a rock shaft t^8 passing through apertures in the arms t^5 and t^6 and journaled in bearings e^1 , e^2 and e^3 formed on the cross-head E^2 . Beyond the juncture of the arms t^5 and t^6 above the shaft t^8 , the hammer is formed with one arm t^{12} adapted for engagement with the trigger T^1 and another arm t^{13} formed with an open-ended socket t^{14} . A bell-crank lever T^2 is pivotally mounted on the shaft t^8 between the arms t^5 and t^6 of the hammer T, and its short arm t^{15} is formed with an open-ended socket t^{16} . The open ends t^{17} and t^{18} of the sockets t^{14} and t^{16} , respectively, face one another, and the sockets are adapted to accommodate a compression spring t^{19} insertable therein through the upper end of the socket t^{14} which is closed by a removable cap t^{20} . The lower ends of the levers t^5 and t^6 form hammer heads t^{21} and t^{22} , respectively, adapted in operation to strike against one side of a cross pin x carried by a lever X^1 connected to the valve X, while the long arm t^{23} of the lever T^2 is adapted to engage the op-

posite side of the pin x and is actuatable to rock the lever X^1 to close the valve X. With the relative movement permitted by having the hammer T fixed to the shaft t^8 and the bell-crank lever T^2 free to pivot thereon, when the hammer is released by the trigger T^1 , the spring t^{19} exercises itself to swing the hammer relatively to the lever T^2 to the dotted line position shown in Fig. 3, whereby the hammer heads t^{21} and t^{22} strike the pin x and rock the lever X^1 to open the valve X. When the hammer T is returned to its full line position to reengage the arm t^{13} with the trigger T^1 , it moves relatively to the lever T^2 and compresses the spring t^{19} . However, the spring t^{19} is so strong that the initial movement of the hammer T acts through the spring t^{19} to rock the lever T^2 until the arm t^{23} thereof engages the pin x and swings the lever X^1 back to its full line position and closes the valve X.

The lever X^1 is vertically disposed and held against sidewise movement by the arm t^{23} of the lever T^2 , the end t^{24} of which is bifurcated to receive the bent upper end x^1 of the lever X^1 . The lower end of the lever X^1 is connected to the valve X which is located in the well D^2 , the lever extending through the body of metal d^2 in the metal pot D and an opening d^{22} formed in a boss d^{23} rising from the wall d^3 and being supported by a yoke x^2 passing through a slot x^3 in the lever and secured therein by a pin x^4 , the ends x^5 (Fig. 10) of the yoke arms x^6 engaging in a groove d^{30} formed in the outer surface of the boss d^{23} . The opening d^{22} is cylindrical, and near its lower end the lever is formed with a rounded portion x^8 which, by its engagement with the walls of the opening d^{22} , permits the lever X^1 to partake of a rocking movement. A finger extension x^9 beyond the spherical portion x^8 of the lever X^1 projects into an opening x^{10} formed in the valve X and provides the connection between the valve and lever. The tendency of the valve X to float in the metal in the well D^2 maintains it well up on the end x^3 of the lever X^1 , as shown in Fig. 3, and it is guided to a proper seating as it is closed by four projections d^{24} formed on the inner end of the throat D^3 around the port d^9 . It is pointed out that even if the valve X did not float, there is not sufficient space between the valve and the bottom of the well to permit it to drop and thus become disconnected from the lever X^1 . In the assembly of the parts, the valve X is located in the well D^2 before the throat D^3 is in place, and the lever X^1 then lowered through the opening d^{22} in the boss d^{23} to engage the end x^9 in the opening x^{10} in the valve. This is accomplished by turning the lever X^1 so that the ends x^5 of the yoke arms x^6 pass through diametrically opposite slots d^{31} leading to the groove d^{30} in the upper end of the boss d^{23} and then turning the lever X^1 to the position shown in Fig. 10.

The operation of the pump actuating mechanism G is controlled by three cams H^3 , H^4 and H^5 (Figs. 1, 2, 6, 12 and 13) fixed to the cam shaft H and operating through yokes h^2 , h^3 and h^4 , respectively, rockably mounted on a shaft H^6 fixed in bosses f^1 on the frame F by a pin h^5 , the yokes being connected to the parts which they actuate by rods h^6 , h^7 and h^8 . As best shown in Fig. 13, the yokes h^2 , h^3 and h^4 carry rollers h^{10} arranged in slots h^{11} and adapted to be engaged by the operating cams H^3 , H^4 and H^5 , respectively. The outer ends of the yokes are connected to the lower ends of the rods h^6 , h^7 and h^8 , each of which is formed with a neck

portion h^{12} and a ball h^{13} and detachably connected to its respective yoke by fitting the ball h^{13} into a recess h^{14} in the end of the yoke with the neck portion h^{12} arranged in an open-ended slot h^{15} , the recess and the end of the slot being closed by a movable cover plate h^{16} (Fig. 13).

The upper end of the rod h^8 is fitted with an adjustable end portion h^{17} having a ball connection with the valve actuating plunger v^{11} (Fig. 14) which moves the slide v^6 . The rod h^7 has a similar adjustable end h^{18} connected to a rock arm h^{19} (Fig. 5) pivoted to the frame as at h^{20} , which arm operates through an interponent h^{21} to actuate the bell-crank lever O^2 and retract the dog O to effect the release of the pump plunger D^6 . The rod h^8 is also provided with an adjustable upper end piece h^{22} which is slidably supported in an aperture formed in a bracket e^4 (Fig. 8) beneath a crank arm t^{25} fixed to one end of the rock shaft t^8 .

The interponent h^{21} is carried at the upper end of a shaft h^{24} rotatably supported in brackets h^{25} and h^{26} and by the rocking of the shaft h^{24} the interponent is adapted to be moved into and out of operative position between the rocker arm h^{19} and the arm o^6 of the bell-crank O^2 , whereby it acts as a safety device to prevent the operation of the pump plunger. The rocking of the shaft h^{24} is controlled by the movement of the metal pot D into and out of casting relation to the mold A , being effected by two bumpers S and S^1 fixed in the frame F to engage an arm h^{27} on the shaft h^{24} . When the metal pot D moves forwardly, it carries with it the shaft h^{24} , and as it moves into casting relation to the mold, the arm h^{27} strikes an adjusting screw s^1 in the bumpers S^1 and rocks the shaft h^{24} to locate the interponent h^{21} in active position between the rocker arm h^{19} and the arm o^6 of the bell-crank lever O^2 . In the event that, for any reason, the metal pot D does not move the full distance to lock the mouthpiece D^4 up tightly against the mold A , the interponent h^{21} will remain in its inactive position and, even though the cam H^5 actuates the yoke h^3 , shaft h^7 and rocker arm h^{19} , the bell-crank lever O^2 will not be actuated to retract the dog O and release the pump operating mechanism. When the pot D returns to its original position after the casting operation, the arm h^{27} strikes the end of an adjusting screw s in the bumper S^1 and rocks the shaft h^{24} to move the interponent h^{21} to its inactive position clear of the rocker arm h^{19} and lever arm o^6 . The bumper S^1 is pivotally mounted so that it can be swung out of the path of the arm h^{27} when desired, in which event the interponent h^{21} will remain in its inactive position and the machine can be operated without casting.

The improved mouthpiece wiping mechanism W comprises a wiping element W^1 mounted at the forward ends of a pair of arms w^1 and w^2 arranged on opposite sides of the metal pot D and fixed at their opposite ends to a shaft w^3 journaled in brackets w^4 rising from the rear end of the carriage E . Intermediate its end, the arm w^1 is connected by a link w^5 (Fig. 1) secured by a screw w^6 to one end of a yoke w^7 (Fig. 13), whose opposite end is rockably supported on the shaft H^6 . Intermediate its ends, the yoke w^7 carries a roller w^8 secured thereto by a bolt w^9 and adapted to track on the periphery of the cam H^2 fixed to the main cam shaft H . At a predetermined point in its periphery in the line of travel of the roller w^8 , the cam H^2 is formed with a recess h^{28}

(Figs. 2 and 12). The leading end of the recess h^{28} falls away sharply as at h^{29} to allow the roller w^8 to drop abruptly therein, and the following end of the recess is formed to provide a surface h^{30} which gradually runs into the periphery of the cam H^2 and on which the roller w^8 rides to raise the yoke w^7 back to its original position. The roller w^8 bears on the periphery of the cam H^2 under the tension of a torsion spring w^{10} surrounding the shaft w^3 and having one end fixed in the frame as at w^{11} and the other end fixed in a collar w^{12} fastened to the shaft w^3 as by a set screw w^{13} .

The wiping element W^1 (Figs. 1, 2, 3 and 6) is journaled at its opposite ends in plates w^{14} pivoted on a shaft w^{15} extending between and fixed to the forward ends of the arms w^1 and w^2 . Each plate w^{14} is formed with a slot w^{16} in which a pin w^{17} formed on the respective arm w^1 or w^2 is adapted to ride, the ends of the slot limiting the movement of the plates w^{14} . The plates w^{14} are normally held forward in the position shown in Figs. 1 and 3 by torsion springs w^{18} associated with each plate and arranged on the rod w^{15} with one end anchored as at w^{19} in each plate and the other end anchored in a collar w^{20} fixed to the rod w^{15} . The wiping element W^1 is normally held against a pin w^{21} on each of the plates w^{14} by a tension spring w^{22} , anchored at one end to the wiping element W^1 and at the opposite end to a pin w^{23} on its respective plate w^{14} , being free to move forwardly, however, against the pull of the springs w^{22} . The reason for the movable mounting of the wiping element W^1 is illustrated in Figs. 1 and 2. In Fig. 1, the wiping element W^1 is in a position for the wiping operation, which takes place just prior to casting. When the roller w^8 drops into the recess h^{28} in the cam H^2 , allowing the yoke w^7 to drop, the spring w^{10} moves the arms w^1 and w^2 downwardly and the wiping element W^1 passes over in front face of the mouthpiece D^4 , bearing against it under the pull of the tension springs w^{22} . After the wiping operation, and as seen in Fig. 2, when the pot D moves into casting relation to the mold A , the wiping element W^1 strikes the mold carrier A^1 and, moving as a unit with the plates w^{14} , yields rearwardly against the tension of the springs w^{18} . After the casting operation, when the metal pot D returns to its rearward position, the springs w^{18} exercise themselves to return the wiping element W^1 to the wiping position, which is determined by the engagement of the pins w^{17} with the ends of the slots w^{16} as shown in Fig. 3.

In the operation of the machine, at the time the line of matrices M is located in casting position, the parts occupy the position shown in Fig. 1, with the line of matrices M , mold A and the pot mouthpiece D^4 in horizontally spaced relation. At the start of the cycle of operation, the parts are in the position shown in Figs. 1 and 12, and as the cam H^2 starts to rotate the mouthpiece wiping operation is effected by the roller w^8 dropping into the recess h^{28} in the cam H^2 to allow the wiping element W^1 to be moved down over the mold engaging face of the mouthpiece D^4 . The roller w^8 then travels over the surface h^{30} of the recess h^{28} and back onto the periphery of the cam H^2 to return the wiper W to the position shown. Continued rotation of the cam shaft H in the direction indicated by the arrow, causes the roller n in the trackway h^1 to ride on the surface h^{35} and be shifted to the right to the position shown in Fig. 2. This rocks the lever N counter-clockwise and, through the rod n^4 , lever N^1

straightens out the toggle link n^{10} and moves the carriage E forwardly, the pot D and plunger actuating mechanism G moving as a unit with the carriage E until the front face of the mouthpiece D⁴ is forced against the rear face of the mold A. As the carriage E completes its forward movement, the arm h^{27} on the vertical shaft h^{24} strikes the screw s^1 in the bumper S¹ and the shaft is rocked to swing the interponent h^{21} at the upper end of the shaft into position between the rock arm h^{19} and the arm o^6 of the lever O² and couple the plunger releasing trip dog O to its actuating mechanism. In the meantime, the mold carrier A¹ is moved to bring the front face of the mold A into engagement with the line of matrices M (see Fig. 2). It will be noted that the forward movement of the carriage E brings the wiping element W¹ into engagement with the top rear edge of the mold carrier A¹, but since the wiping element W¹ is free to swing within the limits of the slots w^{16} , it is merely rocked rearwardly out of its wiping position.

Continued rotation of the cam shaft H brings the low portion h^{36} (Fig. 6) of the cam H⁶ to the top, and the roller h^{10} carried by the yoke h^4 rides down the inclined surface h^{37} , allowing the yoke h^4 and rod h^8 to drop and break the engagement with the upper end h^{22} of the rod and the crank arm t^{25} fixed to the end of the shaft t^8 . Just before the yoke h^4 drops to its lowermost position, the roller h^{10} of the yoke h^3 rides up on the inclined surface h^{38} of the cam H⁴ which controls the operation of the plunger D⁶. The lifting of the yoke h^3 , and with it the rod h^7 , rocks the arm h^{19} upwardly and, through the interponent h^{21} , rocks the bell-crank lever O² to retract the dog O (Fig. 5). This allows the piston G² in the air cylinder G¹ to descend under the influence of the spring g^9 and the head of air pressure constantly maintained above the piston G². The initial downward movement of the piston G² moves the plunger D⁶ sufficiently to cover the ports d^{12} and shut off communication between the body of metal d² and the well D², and also to exert pressure on the body of metal in the well D². However, just as the pressure on the metal in the well D² is built up, the cam surface p^6 on the block P fixed to the lower end of the piston rod G³ completes its camming action on the arm t^1 of the trigger T¹ to rock the trigger arm t^4 out of engagement with the arm t^{12} of the hammer T. The compression spring t^{19} then exercises itself to rock the hammer T counterclockwise so that the heads t^{21} and t^{22} thereof strike the pin x in the lever X¹ a sharp blow to rock the lever X¹ to its dotted line position and thereby open the valve X, the valve being held open by a compression spring h^{23} acting on the arm t^{25} . It may be noted here that the hammer means of opening the valve X is employed both because of the pressure exerted on the metal in the well D² and to open the valve X completely as quickly as possible in order that the volume of metal displaced for casting will be uniform throughout the stroke of the plunger D⁶.

The plunger D⁶ then continues its downward or metal injecting stroke under substantially the same uniform head of pressure to displace the metal in the well D² and force it through the port d^9 and throat passage d^7 into the mold slot a^2 to form the slug, the plunger partaking of a full stroke (under the same uniform head of pressure) regardless of the volume of displaced metal used to fill the mold slot a^2 by virtue of the metal bi-passing through the opening d^{19} (Fig. 75

11) into the main body of metal d² in the crucible D¹ after the mold is filled.

The roller h^{10} in the yoke h^3 then rides down an inclined surface h^{39} on the cam H⁴, allowing the yoke and rod h^7 to drop so that the bell-crank lever O² is free to be returned to its full line position (Fig. 5) under the influence of the spring O⁴. As the roller h^{10} of the yoke h^3 rides off the surface h^{39} , the roller h^{10} carried by the yoke h^2 rides up an inclined surface h^{40} on the cam H³, raising the yoke h^2 and the rod h^6 fixed to the lower end of the plunger v^{11} in the valve V (Fig. 14). This moves the valve plunger v^{11} and the slide v^6 upwardly to establish communication, through the passage v^{21} , between the intake port v^{16} and the port v^{20} to admit air from the supply pipe J to the pipe v^1 leading from the valve V to the bottom of the air cylinder G¹ below the piston G². At the same time, communication is established by the recess v^{18} in the valve slide v^6 between the port v^{17} and the port v^{19} communicating with the exhaust pipe K. The air entering the bottom of the cylinder G¹ forces the piston G² upwardly to retract the plunger D⁶, air being exhausted from the top of the cylinder through the pipe v , recess v^{18} in the slide v^6 and the port v^{19} communicating with the exhaust pipe K.

When the plunger D⁶ is completely retracted, the dog O is returned to its operative position below the block P to hold the piston G² in its upper position, and the roller h^{10} in the yoke h^2 rides down an inclined surface h^{41} on the cam H³, allowing the yoke and rod h^6 to drop and return the slide v^6 to the position shown in Fig. 14, admitting air once again to the pipe v leading to the top of the cylinder G¹. After the start of the return stroke of the plunger D⁶, the roller h^{10} in the yoke h^4 rides up an inclined surface h^{42} onto the periphery h^{43} of the cam H⁶, raising the yoke h^4 and rod h^8 and causing the upper end h^{22} of the rod h^8 to engage the end of the crank arm t^{25} to rock the shaft t^8 clockwise and return the hammer T to its original position, the arm t^4 of the trigger T dropping down to engage the hammer arm t^{12} . During the initial rocking of the shaft t^8 , the spring t^{19} tends to compress, but it is strong enough so that it rocks the arm t^{23} of the lever T² counterclockwise against the crosspin x to move the lever X¹ and close the valve X, very little force being necessary for this purpose since the metal in the well D² is not under pressure, as was the case when the valve X was opened. When the valve X is closed, the lever X¹ then resists the movement of the lever T², and continued rocking of the shaft t^8 compresses the spring t^{19} to place it under tension. It will be noted that the retraction of the plunger D⁶ is commenced shortly before the valve X is closed, thus allowing a back draft of the metal in the throat passage d^7 sufficiently to avoid its leakage through the mouthpiece openings d^8 when the pot D is moved out of casting relation to the mold.

The roller n on the bell-crank lever N rides on an inclined surface h^{44} (Figs. 1 and 2) of the cam H² and is moved to the left to rock the lever N clockwise and return the pot carriage E to its original position shown in Fig. 1. As the metal pot D returns to its initial position, the arm h^{27} on the vertical shaft h^{24} strikes the screw s in the bumper S and rotates the shaft h^{24} to move the interponent h^{21} out from between the rocker h^{19} and the arm o^6 of the bell-crank lever O², thus uncoupling the plunger releasing mechanism to prevent the release of the plunger D⁶. The

cam shaft H then completes its rotation to end the cycle of operation of the machine.

It will be seen now that the present invention affords an arrangement wherein the metal pot and plunger actuating mechanism, mounted on a common carrier adapted for horizontal movement on rollers, are easily moved as a unit into and out of casting position, the movement being quick and smooth. The injection of metal into the mold by subjecting it to a head of pressure while in the pot and then suddenly opening the valve to release it for introduction into the mold while maintaining substantially the head of pressure built up before its release, fills the mold completely with metal flowing thereinto at a uniform high velocity and under uniform pressure. After the mold is filled, the metal therein is maintained under the same uniform pressure until the plunger completes its stroke, with the result that, the mold having been filled completely and rapidly, the dense body of metal in the mold is afforded an opportunity to chill and solidify for a long enough period of time to prevent a back-draft of metal from the mold when the plunger is retracted. The pneumatic operation of the plunger, in addition to the improved result in casting which it affords, adds to the smoothness of operation of the entire casting mechanism, the necessary relative movements of the pot and plunger actuating mechanism found in the spring actuated devices being obviated along with the stresses and strains and wear of the parts resulting from the tensioning of the heavy plunger actuating spring. In the present instance, the mechanism is compact and the parts are, in the main, of light weight, since there is little or no heavy work to be done. Many other advantages will be manifest to those skilled in the art without specific recitation herein.

Having thus described my invention, what I claim is:

1. In a typographical casting machine, the combination of a mold, and mechanism for injecting metal into the mold including a fluid actuated plunger adapted to subject the metal to pressure and thereafter, when the maximum pressure has been built up suddenly effect the introduction of the metal into the mold under substantially uniform pressure.

2. In a typographical casting machine, the combination of a mold, and mechanism for injecting metal into the mold including a fluid actuated plunger adapted to subject the metal to a head of pressure and thereafter suddenly effect the introduction of the metal into the mold while maintaining it under substantially said head of pressure.

3. In a typographical casting machine, the combination of a mold, mechanism for injecting metal into the mold including a fluid actuated plunger adapted to subject the metal to pressure and acting to exert substantially uniform pressure on the metal during the injection thereof into the mold, and means operable when the metal is subjected to pressure for effecting its introduction into the mold.

4. In a typographical casting machine, the combination of a mold, mechanism for injecting metal into the mold including a fluid actuated plunger adapted to subject the metal to substantially uniform pressure during its metal injecting stroke, a valve adapted to be opened to effect the introduction of the metal into the mold, and means operative to open the valve when the metal is subjected to pressure by the plunger.

5. In a typographical casting machine, the combination of a mold, mechanism for injecting metal into the mold including a fluid actuated plunger adapted to subject the metal to substantially uniform pressure during its metal injecting stroke, a valve adapted to be opened to effect the introduction of metal into the mold, and means operative to open the valve after the plunger has commenced its metal injecting stroke and subjected the metal to pressure.

6. In a typographical casting machine, the combination of a mold, mechanism for injecting metal into the mold including a fluid actuated plunger for displacing the metal to force it into the mold and adapted to subject the metal to substantially uniform pressure during its metal injecting stroke, a valve adapted to be opened to effect the introduction of metal into the mold, means operative to open the valve after the plunger has commenced its metal injecting stroke and subjected the metal to pressure, and means to render the plunger operative to partake of a full metal injecting stroke regardless of the volume of metal forced into the mold.

7. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to substantially uniform pressure throughout its metal injecting stroke, a valve for closing said passage, and means operative to open the valve by a sudden hammer-blow action thereon after the plunger has commenced its metal injecting stroke and subjected the metal in the chamber to pressure.

8. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to a head of pressure and to maintain said head of pressure on the metal throughout its metal injecting stroke, a valve for closing said passage, and means operative to open the valve by a sudden hammer-blow action thereon after the plunger has commenced its metal injecting stroke and subjected the metal in the chamber to the full head of pressure.

9. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to substantially uniform pressure throughout its metal injecting stroke, a ball valve arranged to close said metal injecting passage, a lever pivoted intermediate its ends and connected on one side of the pivot to the valve, and means operative to strike the lever on the opposite side of the pivot a hammer-like blow to open the valve after the plunger has commenced its metal injecting stroke and subjected the metal in the chamber to pressure.

10. In a typographical casting machine, the combination of a mold, a metal pot having a metal confining chamber formed therein, a metal injecting passage leading from the chamber, a fluid actuated plunger for injecting metal into

the mold through said passage, said plunger operating to subject the metal in the chamber to substantially uniform pressure throughout its metal injecting stroke, a ball valve arranged to close said metal injecting passage, a lever pivoted intermediate its ends and connected on one side of the pivot to the valve, and spring actuated means operative to strike the lever on the opposite side of the pivot a hammer-like blow to open the valve after the plunger has commenced its metal injecting stroke and subjected the metal in the chamber to pressure.

11. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to substantially uniform pressure throughout its metal injecting stroke, a ball valve arranged to close said metal injecting passage, a lever pivoted intermediate its ends and connected on one side of the pivot to the valve, and spring actuated means operative to strike the lever on the opposite side of the pivot a hammer-like blow to open the valve after the plunger has commenced its metal injecting stroke and subjected the metal in the chamber to pressure, said valve opening means being controlled by a trigger arranged to be tripped by means operative in response to the movement of the plunger in its metal injecting stroke.

12. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to substantially uniform pressure throughout its metal injecting stroke, a ball valve arranged to close said metal injecting passage, a lever pivoted intermediate its ends and connected on one side of the pivot to the valve, and spring actuated means operative to strike the lever on the opposite side of the pivot a hammer-like blow to open the valve after the plunger has commenced its metal injecting stroke and subjected the metal in the chamber to pressure, said valve opening means being controlled by a trigger arranged to be tripped by means operative in response to the movement of the plunger in its metal injecting stroke, and means acting positively to close the valve after the mold has been filled with metal.

13. In a typographical casting machine, the combination of a mold, a metal pot having a metal confining chamber formed therein, a metal injecting passage leading from the chamber, a fluid actuated plunger for injecting metal into the mold through said passage, said plunger operating to subject the metal in the chamber to substantially uniform pressure throughout its metal injecting stroke, a ball valve arranged to close said metal injecting passage, a lever pivoted intermediate its ends and connected on one side of the pivot to the valve, and spring actuated means operative to strike the lever on the opposite side of the pivot a hammer-like blow to open the valve after the plunger has commenced its metal injecting stroke and subjected the metal in the chamber to pressure, said valve opening means being controlled by a trigger arranged to be tripped by means operative in response to the

movement of the plunger in its metal injecting stroke, and means acting positively to close the valve and reset the valve opening means when the plunger is retracted after completing its metal injecting stroke.

14. In a typographical casting machine, the combination of a mold, a metal pot movable from inactive to active position to cooperate with the mold for casting, a plunger in the metal pot for injecting metal therefrom into the mold, means for holding the plunger against operation, means connected thereto for effecting the release of the plunger, and means actuatable by the movement of the metal pot from one position to the other to couple and uncouple the plunger holding and releasing means.

15. In a typographical casting machine, the combination of a mold, a metal pot movable from inactive to active position to cooperate with the mold for casting, a plunger in the metal pot for injecting metal therefrom into the mold, means for holding the plunger against operation, means connected thereto for effecting the release of the plunger, and means for coupling and uncoupling the plunger holding and releasing means, said means being uncoupled when the metal pot is in inactive position and being coupled thereto by the movement of the metal pot into active position.

16. In a typographical casting machine, the combination of a mold, a metal pot movable into and out of casting position relatively to the mold, a plunger in the metal pot for injecting metal therefrom into the mold, means for operating the plunger to inject metal into the mold, means to hold said operating means inactive, means to actuate said holding means to release the plunger operating means, and an interponent movable to and from active position for coupling and uncoupling said actuating means and said holding means, said interponent occupying its inactive position when the metal pot is out of casting relation to the mold and being moved to its active position when the metal pot moves into casting relation to the mold.

17. In a typographical casting machine, the combination of a mold, a metal pot movable into and out of casting position relatively to the mold, a plunger in the metal pot for injecting metal therefrom into the mold, a fluid operated piston for actuating the plunger, a trip dog for holding the piston against movement to operate the plunger, means actuatable to release said dog, and an interponent movable into and out of active position to establish a connection between the dog and its releasing means, said interponent being moved into active position by the movement of the metal pot into casting position.

18. A combination according to claim 17, wherein the interponent is fixed to a rock shaft, and including two bumpers mounted in the machine and adapted to be engaged by an arm on the rock shaft during the movement of the metal pot, one bumper being located for engagement with said arm when the pot moves into casting relation to the mold and the other bumper being located for engagement with the arm when the pot moves to non-casting position.

19. A combination according to claim 17, wherein the interponent is fixed to a rock shaft, and including two bumpers mounted in the machine and adapted to be engaged by an arm on the rock shaft during the movement of the metal pot, one bumper being located for engagement with said arm when the pot moves into casting

relation to the mold and the other bumper being located for engagement with the arm when the pot moves to non-casting position, said first mentioned bumper being movable into and out of the path of said arm at will, whereby the machine can complete a cycle of operation without casting.

20. In a typographical casting machine, the combination of a mold, a metal pot movable into and out of casting relation to the mold, and means for moving the metal pot including a ¹⁰ toggle which has an adjustable throw to locate

the metal pot accurately in casting position when the toggle is expanded.

21. A combination as in claim 20, wherein one end of the toggle is secured to an anchoring member fastened to a fixed part of the machine, and an adjustable wedge-shaped interponent is provided to vary the location of the anchoring member relatively to the part of the machine to which it is fastened.

JAMES C. PLASTARAS.
